UNITED STATES PATENT OFFICE

CARL F. STOLTZ, OF DELHI, OHIO, AND GEORGE W. FERLING, OF INDIANAPOLIS, INDIANA, ASSIGNORS TO THE UNION SWITCH & SIGNAL COMPANY, OF SWISSVALE, PENNSYLVANIA, A CORPORATION OF PENNSYLVANIA

APPARATUS FOR TESTING AUTOMATIC TRAIN-CONTROL EQUIPMENT

Application filed June 2, 1928. Serial No. 282,457.

Our invention relates to apparatus for testing automatic train control equipments, and particularly for testing the train-carried equipment of intermittent inductive train control systems of the type involving a normally energized train-carried receiver.

We will describe two forms of apparatus embodying our invention, and will then point out the novel features thereof in claims.

In the accompanying drawing, Fig. 1 is a diagrammatic view showing one form of apparatus embodying our invention. Fig. 2 is a diagrammatic view showing a modification of a portion of the apparatus shown in Fig. 1 and also embodying our invention.

Similar reference characters refer to similar parts in each of the views.

Referring first to Fig. 1, the reference characters 1 and 1^a designate the track rails of a railway along which traffic normally moves in the direction indicated by the arrow. In the trackway is a winding 4 located in such position that current is induced therein by the receiver of a train-carried equipment. This winding is placed on a magnetizable core 3, so that the assembly of the core and winding is similar to the inert roadside element ordinarily provided in train control systems of the type referred to hereinbefore. This assembly is designated as a whole by the reference character D. The winding 4 supplies current to a relay R¹, which relay is therefore normally de-energized but becomes momentarily energized by the current induced in the winding 4 during the passage of an energized train-carried receiver. Located in advance of the winding 4 is a track section A—B electrically isolated by means of insulated joints 2, and connected across the rails of this section is a relay R², which relay functions as a stick relay. The pick-up circuit for relay R² is from a battery C, through front contact 5 of relay R¹, lower rail 1^a of section A—B, winding of relay R², and upper rail 1 of section A—B to battery C. It follows that during the momentary energization of relay R¹, relay R² becomes energized; a stick circuit for relay R² then

becomes closed, which circuit is from battery C, through front contact 6 of relay R², rail 1^a of section A—B, winding of relay R², and rail 1 of section A—B to battery C. Relay R² therefore remains energized until the train enters section A—B whereupon the wheels and axles of the train shunt the current from battery C away from relay R² and the relay then becomes de-energized.

The reference character I¹ indicates an indicating device, such as a signal lamp, which may be located in the trackway where it is visible to the engineman. The reference character I² indicates another indicating device, which may be located in a despatcher's office. The two indicating devices I¹ and I² are connected in multiple, and the circuit for these devices is controlled by front contact 7 of relay R², so that these devices are both lighted while relay R² is energized and are extinguished when the relay is de-energized.

Apparatus embodying our invention will usually be located at a point where the engine crew is changed, and the purpose of the apparatus is to enable the relieving engineman on a through run to establish to his own satisfaction that the train-carried equipment of the automatic train control system is in operating condition. As the train-carried receiver passes over the winding 4, it momentarily energizes relay 5, thereby energizing relay R² and lighting the indicating devices I¹ and I². The fact that the indicating device I¹ is lighted, indicates to the engineman that the receiver of his train-carried apparatus is energized, and the fact that the device I² is lighted gives the same information to the despatcher.

If the resistance of relay R¹ is very low, the winding 4 and magnetizable core 3 will function in the same manner as an inert roadside element, the winding of which is on closed circuit, and it would not be necessary for the engineer to perform the usual acknowledging action in order to prevent an application of the brakes. It is desirable, however, that this acknowledging action should be required upon passing over the

winding 4 in order to check the operation of the acknowledging portions of the apparatus, as well as to check energization of the receiver. For this reason, the resistance of relay R^1 is preferably relatively high, so that the effect of the device D is the same as the effect of an inert roadside element the winding of which is on open circuit. The result of this is that the engineer must perform the acknowledging action upon passing over the device D in order to prevent an automatic application of the brakes.

With the arrangement of the apparatus shown in Fig. 1, relay R^2 , which is connected with the rails of track section A—B, is normally de-energized. When this section is in automatic train control territory, the relay connected with the rails of the section must, of course, be normally energized, and for such locations the modification shown in Fig. 2 may be used. In Fig. 2, section A—B is provided with the usual track circuit comprising a source of current 9 and a track relay T. The pick-up circuit for relay R^2 includes contact 5 of relay R^1 , so that this relay becomes energized when relay R^1 is momentarily energized due to the passage of an energized train-carried receiver over the device D. Relay R^2 is provided with a stick circuit which passes from battery C, through front contact 6 of relay R^2 , front contact 8 of track relay T, and the winding of relay R^2 to battery C. It follows that when relay R^2 becomes energized, it remains energized until track relay T becomes de-energized due to the entrance of the train into section A—B. The control of the indicating devices I^1 and I^2 by contact 7 of relay R^2 is the same as in Fig. 1.

One form of train control system with which our invention may be used, is illustrated and described in application for Letters Patent of the United States, filed by P. N. Bossart on January 29, 1926, Serial No. 84,588, although the present invention is not limited to use in connection with the specific system illustrated in the said application.

Although we have herein shown and described only two forms of apparatus embodying our invention, it is understood that various changes and modifications may be made therein within the scope of the appended claims without departing from the spirit and scope of our invention.

Having thus described our invention, what we claim is:

1. Roadside apparatus for testing the train carried equipment of an intermittent inductive train control system of the type involving a normally energized train carried receiver, said apparatus comprising a winding located in the trackway in such position as to have current induced therein by the receiver during the passage of a train,

a relay connected with said winding and arranged to be momentarily energized by the current induced in the winding by the train carried receiver, a stick relay having a pick-up circuit controlled by a front contact of said first relay and a stick circuit excluding the front contact of the first relay but including a front contact of the stick circuit, means including a track circuit located in advance of said winding for opening said stick circuit, and an indicating device controlled by said stick relay.

2. Roadside apparatus for testing the train carried equipment of an intermittent inductive train control system of the type involving a normally energized train carried receiver, said apparatus comprising a winding located in the trackway in such position as to have current induced therein by the receiver during the passage of a train, a relay connected with said winding and arranged to be momentarily energized by the current induced in the winding by the train carried receiver, a track section located in advance of said winding, a track relay connected across the rails of said section, a source of current connected across the rails of said section through a front contact of said first relay whereby said track relay is normally de-energized but becomes energized when said first relay is energized, a branch around said front contact of said first relay including a front contact of said track relay whereby when the track relay becomes energized it remains energized until the train enters said track section, and an indicating device controlled by said track relay.

In testimony whereof we affix our signatures.

CARL F. STOLTZ.
GEORGE W. FERLING.
